UNITED STATES PATENT OFFICE

110,920

DESIGN FOR A BREAD SLICING MACHINE

Sander Debus, Hastings, Nebr., assignor to U. S.
Slicing Machine Company, La Porte, Ind., a
corporation of Indiana

Application May 23, 1938, Serial No. 77,349

Term of patent 14 years

To all whom it may concern:

Be it known that I, Sander Debus, a citizen of the United States, residing at Hastings, Adams County, Nebraska, have invented a new, original, and ornamental Design for a Bread Slicing Machine, of which the following is a specification, reference being had to the accompanying drawing, forming part thereof, showing my new design.

Fig. 1 is a front perspective view of a bread slicing machine embodying my new design, showing the knife bracket in lowered position; and

Fig. 2 is a side elevational view thereof with the knife bracket in raised position.

I claim:

The ornamental design for a bread slicing machine, as shown and described.

SANDER DEBUS.
